United States Patent Office

Des. 181,005

Patented Sept. 17, 1957

181,005

BATH ROOM SCALE

Lucille E. Hansen, Northbrook, Ill.

Application September 25, 1956, Serial No. 43,085

Term of patent 14 years

(Cl. D52—10)

FIG. 1

FIG. 2

I claim:

The ornamental design for a bath room scale, as shown.
